UNITED STATES PATENT OFFICE

CHARLES A. CULVER, OF NORTHEFIELD, MINNESOTA, ASSIGNOR TO WIRED RADIO, INC.,
OF NEW YORK, N. Y., A CORPORATION OF DELAWARE

MODULATION SYSTEM

Application filed August 3, 1928. Serial No. 297,200.

My invention relates to modulating systems in general and more specifically to systems for modulating the energy of continuous wave transmitters.

5 An object of my invention is to provide an improved modulating system for continuous wave transmitters.

Another object of my invention is to provide an improved modulating system for 10 radio telephone and broadcast transmitters whereby a minimum of distortion is produced.

Still another object of my invention is to provide an improved system for modulating 15 the energy of continuous wave high frequency transmitters employing electrically balanced circuit arrangements of thermionic tubes.

A better understanding can be had of the 20 modulation system of my invention by referring to the specification following and to the accompanying drawing wherein is illustrated the modulation system of my invention.

25 A diagrammatic circuit arrangement is shown employing in combination a high frequency electrical generating circuit, a balanced amplifier circuit, a modulation circuit, and a load circuit which might be a space

30 radio radiating system as illustrated, a wired radio system, or additional amplifier circuits.

The high frequency generator includes thermionic tube 1, having control electrode 2, cathode 3 and anode 4. Control electrode or

35 grid circuit 5 includes mechanically vibratile element 7 which may be any means for sustaining oscillations of constant frequency, such as a quartz crystal having piezo electric properties. Radio frequency choke coil 9

40 excludes radio frequency energy from source of grid biasing potential 10. The anode or plate circuit 6 of thermionic tube 1 includes radio frequency inductance-capacity circuit 8 and source of anode potential 12. Circuit

45 8 is coupled to input circuits 13 and 18 of thermionic tubes 14 and 28 respectively. Electrodes 2, 3 and 4 of thermionic tubes 14 and 28 correspond to electrodes 2, 3 and 4 of thermionic tube 1. Thermionic tubes 14

50 and 28 have a common output circuit 15, the

energy from which is transferred to load circuit 20. Load circuit 20 may be a wired radio system, additional amplifiers, or as illustrated, a space radio radiating system. Anode potential for thermionic tubes 14 and 28 is supplied from source 22. Capacity 16 completes the radio frequency output circuit. The anode potential of thermionic tubes 14 and 28 is governed by the resistance of thermionic tube 23. The anode-cathode 60 resistance of thermionic tube 23 is in series with source of potential 22 and anodes 4 of thermionic tubes 14 and 28. Electrodes 2, 3 and 4 of thermionic tube 23 correspond to electrodes 2, 3 and 4 of thermionic tube 14. 65 Radio frequency choke coil 17 excludes radio frequency energy from thermionic tube 23. A source of current variations is produced by variable resistor 27 and source of potential 26. Variations of electrical energy are 70 transferred to control electrode-cathode circuit 24 by transformer 25. Source of potential 29 provides the proper operation of thermionic tube 23 by selecting the proper part of the characteristic curve. Variable 75 resistor 27 is herein illustrated as an ordinary telephone microphone.

It is obvious that any source of variable electrical energy may be employed, for example a light-sensitive cell of selenium. Variations of potential add to or subtract from the normal operational potential of control electrode 2. Variations of potential supplied control electrode-cathode circuit 24 produce corresponding changes in the anode-cathode 80 resistance of thermionic tube 23. As the resistance of thermionic tube 23 is varied or modulated, the potential supplied anodes 4 of thermionic tubes 14 and 28 will be likewise varied or modulated. 85

It is obvious that the modulation system of my invention may be employed in systems wherein only high frequency generators are employed. In such arrangements the modulation system of my invention may be employed in a similar arrangement to that illustrated in the accompanying drawing wherein in the system is applied to thermionic tube amplifier systems. As a result of this arrangement, the power output of the high fre- 95 100

quency generator system will be controlled in strict accordance with the voice-generated potential impressed upon the modulator tube and distortion of the audio frequency is therefore prevented.

The modulation system of my invention has other advantages. In the constant current system of modulation power voltages developed across the inductance forming the choke, are in many instances excessively high, with the result that the oscillator or amplifier tubes are compelled to carry a load whose value is many times the non-signaling value. As an example suppose that the oscillator or amplifier tubes are overloaded four times the non-signaling value and an average of three halves the non-signaling value. Unless excessively large tubes are used, the tubes are overloaded and consequently a material shortening of their life results. In the modulation system of my invention, the absence of the large choke inductance prevents distortion. It is a well known fact that the voltage developed at the terminals of the choke in the constant current system will be a function of the frequencies impressed upon the inductance. The result follows that the wave form will be distorted, and hence the wave form of the voltage curve impressed upon the oscillator or power amplifier will not be a replica of the voltage curve impressed upon the grid of the modulator tube. In the modulation system of my invention the power is controlled or modulated by what amounts to an ohmic resistance. The distortion, which results from employing inductance, is therefore avoided. Batteries are illustrated in the accompanying drawing and referred to in the foregoing specification. It is obvious that any suitable source of energy may be employed. It should be understood that my invention may be employed in circuits other than the one shown in the accompanying drawing.

It is to be further understood that a crystal controlled driver circuit is not essential but that any master oscillator or source of high frequency energy may be employed. I realize that many modifications of the modulation system of my invention are possible and it is to be understood that my invention is not restricted to the accompanying drawing or to the foregoing specification but only as defined in the appended claims.

55 I claim:

1. In a modulation system the combination of thermionic tubes having cathode, control electrode and anode electrodes, said thermionic tubes connected in an electrically balanced circuit arrangement, common potential supply for said anodes, a thermionic tube having cathode, control electrode and anode electrode, the anode-cathode resistance of said last mentioned thermionic tube connected in series with the common anode potential

supply to said first mentioned thermionic tubes.

2. A modulation system comprising in combination electrically balanced circuit arrangements of thermionic tubes and a thermionic tube connected in series with a common source of energy supplied to the anodes of said first mentioned thermionic tubes whereby the resistance of said last mentioned thermionic tube controls the energy supplied said first mentioned thermionic tubes. 70 75

3. A modulation system comprising in combination electrically balanced circuit arrangements of thermionic tubes employed as amplifiers and a thermionic tube having its cathode-anode resistance connected in series with a common source of electrical energy supplied to the anodes of said balanced thermionic tube amplifiers. 80

4. A system for modulating high frequency energy comprising in combination thermionic tubes connected in a balanced amplifier arrangement, said thermionic tubes having common anode circuits, a common source of anode potential for said anode circuits, and the anode-cathode resistance of another thermionic tube connected in series with the anode supply potential of said first mentioned thermionic tubes. 85 90

5. A broadcasting system comprising in combination a source of high frequency signaling energy, thermionic tubes connected in an electrically balanced circuit arrangement, said thermionic tubes having a common source of anode potential, a thermionic tube the resistance of which is electrically connected in series with said source of anode potential and means for varying the resistance of said last mentioned thermionic tube thereby varying the potential supplied said anodes. 95 100 105

6. A system for modulating high frequency signaling energy according to low frequency variations comprising in combination electrically balanced thermionic tube generators having a common source of anode potential, a thermionic tube the resistance of which is electrically connected in series with said source of anode potential and means for causing the resistance of said last mentioned thermionic tube to vary according to variations of current impressed thereon. 110 115

7. A modulation system comprising in combination a source of high frequency signaling energy, a plurality of thermionic tubes employed in electrically balanced amplifier circuit arrangements, said thermionic tubes having a common source of anode potential, a thermionic tube the anode-cathode resistance thereof connected in series with said source of anode potential, and means for varying the resistance of said last mentioned thermionic tube according to fre- 120 125 130

quencies of a lower order than said high frequency.

8. A radio signaling system comprising means for radiating oscillations, an electron tube oscillation generator associated with said radiating means, a push-pull electron tube amplifier interposed between said radiating means and said oscillation generator, a source of anode potential for said amplifier, and means including an electron tube 10 the internal resistance of which is in series with said source of anode potential for varying the anode excitation applied to said amplifier in accordance with a desired modulation of signaling waves.

15 In testimony whereof I affix my signature.
